UNITED STATES PATENT OFFICE.

JOHN H. MCQUAID, OF GOODHOPE, WEST VIRGINIA.

NECKTIE-FASTENER.

SPECIFICATION forming part of Letters Patent No. 699,341, dated May 6, 1902.

Application filed September 10, 1901. Serial No. 74,973. (No model.)

To all whom it may concern:

Be it known that I, JOHN H. MCQUAID, a citizen of the United States, residing at Goodhope, in the county of Harrison and State of West Virginia, have invented certain new and useful Improvements in Necktie-Fasteners; and I do hereby declare the following to be a full, clear, and exact description of the invention, such as will enable others skilled in the art to which it appertains to make and use the same.

This invention has relation to means for the securement of neckties to prevent their vertical and lateral displacement; and it consists of the novel features, details of construction, and combinations of the parts which herein-after will be more particularly set forth, illustrated, and finally claimed.

In the drawings, Figure 1 is a perspective view of a necktie and meeting ends of a collar embodying the invention, the necktie being detached from the collar-button. Fig. 2 is a central longitudinal section of the collar-button with the plate in position, the dotted lines showing the necktie. Fig. 3 is a view of the parts shown in Fig. 2 in section on a plane at a right angle to the section shown in Fig. 2. Fig. 4 is a perspective view of the fastener, the parts being separated.

Corresponding and like parts are referred to in the following description and indicated in all the views of the drawings by the same reference characters.

The fastener consists of two members or parts, one being attached to the necktie and the other forming a part of the collar-button, which is used in the ordinary way for securing the ends of a collar and for attaching the latter to the shirt-band.

The collar-button comprises the stem or body 1, back 2, and front 3, and in accordance with this invention it is provided with a head 4 of approximately rounded form with its opposite sides flattened, as shown at 5. The head 4 is hollow, although this is not essential, and is provided with parallel slits or cuts 6, extending at a right angle to the flattened sides 5 of the head. These slits 6 extend inward a sufficient distance to admit of the side portions of the head moving inward and springing outward when released from the compressing influence pressing the sides

together. The slits 6 must also be of a width to admit of an appreciable movement of the side portions of the head.

The collar-button is used in the well-known manner of applying devices of this character, and when in position the head 4 projects outward from the collar, as shown most clearly in Fig 1, the flattened sides preferably occupying a horizontal position.

The stem or body 1 of the collar-button is flattened, so as to prevent turning of the button when applied to the neckband of the shirt and after the collar has been buttoned thereto. The flat sides of the stem are gripped by opposite edges of the buttonholes of the collar and neckband and prevent turning of the button, and consequently hold it in a given position.

The coöperating member 7 of the fastener consists of a plate adapted to be attached to the necktie 8 by stitching or in any selected way and a socket 9, having opposite sides flattened and approximating the outline of the head 4. The mouth of the socket 9 is oblong, conforming in outline to the profile of the head 4 in front view. The socket 9 is split, as shown at 10, and this split extends through an edge of the plate, whereby provision is had for the ready removal of the tool employed in the formation of the member 7. This member 7 is attached to the necktie and snaps over the head 4 of the collar-button, and by reason of the flattened sides of the head 4 and socket 9 the latter is prevented from turning upon the head. Hence the necktie is held in proper position.

Having thus described the invention, what is claimed as new is—

1. In a necktie-fastener, a member having a rounded head with its opposite sides flattened and having corresponding cuts extending inward about at a right angle to the plane of the flattened sides to form yielding side portions, and a companion member having an oblong opening and a socket extended from the plate in line with the opening and having its opposite sides flattened, said socket and an edge portion of the plate being split, substantially as set forth.

2. In a necktie-fastener, a collar-button comprising a flat stem, a front and a back and a head having flattened sides and inwardly-

extending cuts, and a member for attachment to a necktie and comprising a plate having an oblong opening and a socket extended from the plate in line with the opening and having 5 its opposite sides flattened, said socket and an edge portion of the plate being split, substantially as set forth.

In testimony whereof I affix my signature in presence of two witnesses.

JOHN H. MCQUAID.
